(57) **CLAIM**

The ornamental design for a ball returner, as shown and described.

DESCRIPTION

FIG. 1 is a perspective view of a ball returner;
FIG. 2 is a side elevation thereof, the opposite side being identical;

FIG. 3 is a front elevation thereof;

FIG. 4 is a bottom view thereof; and,

FIG. 5 is a perspective view thereof, the goal shown in broken lines being for illustrative purposes only; and forming no part of the claimed design.
